UNITED STATES PATENT OFFICE

2,285,214

DISPLAY DEVICE

Dallas V. Lisle, Pittsburgh, Pa.

Application December 16, 1940, Serial No. 370,390

2 Claims. (Cl. 211—69)

This invention relates to display devices of the cardboard self-supporting foldable type commonly used for displaying articles of merchandise to promote the sales thereof, and the general object of the present invention is to provide a device of that character which not only allows ready application and removal of the articles with respect thereto when either in folded or displayed positions, without possibility of damaging the device, but the device can be instantly set up or folded, with the articles mounted with respect thereto, as the articles do not in any way interfere with the folding or setting up of the device, nor do they have any function for connecting the parts or portions of the device together or for holding it in displayed position, and the particular construction of my device allows it to be folded in compact form, so as to take up minimum space in storage.

A further object is to provide a display device that is self-supporting, in a manner to prevent it from toppling over and from collapsing or casual folding.

Another object is to provide a display device that has ample space on the front face thereof for indicia such as advertising matter, so that the indicia will not be unduly obstructed by the displayed articles, and the device is simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a front perspective view of one form of my device for displaying writing implements such as pencils and like shaped articles.

Figure 2 is an edge elevation thereof in folded position.

Figure 3 is a view of the blank from which the form of Figures 1 and 2 is made.

Figure 4 is an edge elevation of a modified form which allows adjustment of the front or body portion thereof to several inclined positions, and the front portion of this form is free from article fastening or supporting cut out members or the like, so that the front portion can be used for advertising purposes only, or portions can be

cut therefrom to fit articles of any kind and shape.

Figure 5 is a view of a fragmentary portion of the blank from which the form of Figure 4 is made.

Figure 6 is a front perspective view of a further modified form for displaying writing implements and the like.

Figure 7 is a rear perspective view of the form of Figure 6.

Figure 8 is an edge elevation of the form of Figures 6 and 7 in folded position.

Figure 9 is a view of the blank from which the form of Figures 6 to 8 is made.

Referring to the drawing in detail, it will be noted that each of the forms of my device is made from a single blank of any suitable sheet material, such as cardboard or the like.

The blank of the form of Figures 1 and 2, as shown in Figure 3 is of elongated rectangular shape and is provided with three transversely disposed parallel score or fold lines 1, 2 and 3, the line 1 being arranged along the transverse center of the blank, the line 2 in close proximity to the line 1, and the line 3 is arranged a greater distance from the line 2 than the latter is from the line 1, so that when the blank is bent along the lines 1 and 3 when forming the device, there is provided a relatively large front or body portion 4, a narrow base portion 5 and a relatively small brace portion 6. The base portion is bent upwardly along the score line 2 to provide converging sections 7 and 8, and the rear section is of greater width than that of the front section, so that the front or body portion can be supported at a rearward inclination slightly beyond a vertical plane.

The blank is further provided with a score or fold line 9 extending transversely thereof adjacent to the free end of the brace portion 6 to provide a hinge strip 10 that is adhesively or otherwise fixed to the rear face of the front portion 4 substantially along the transverse center thereof, so that when the device is set up in displayed position, the front and brace portions are disposed in converging relation, with the front portion inclined rearwardly and supported accordingly by the brace and base portions as clearly shown in Figure 1.

Struck from the front portion 4 is a relatively narrow flap 11 that extends transversely and forwardly therefrom for disposal horizontally when the device is in displayed position, and the flap has a row of openings 12 therein for receiving writing implements such as pencils A, or any other

er like shaped articles. The front portion 4 also has struck therefrom substantially triangular shaped ears 13 arranged in pairs and forwardly directed from the portion 4 to provide substantially V-shaped pockets aligned with the openings 12 to receive the lower ends of the writing implements, as clearly shown in Figure 1. By that construction, it will be obvious that the writing implements can be easily and expeditiously applied and removed with respect to the display device without possibility of damaging the latter and when the device is in either folded or displayed position, and it will be further obvious that the device is foldable merely by moving the front and brace portions together and to displayed position by separating said portions.

The front portion 4 may have any suitable indicia thereon such as advertising matter, as shown, or descriptive matter relative to the pencils, and due to the arrangement of the pencil fastening and supporting means with respect to the portion 4, the indicia is not unduly obstructed, as will be noted upon inspection of Figure 1.

The form of Figure 4 also includes a front portion 14, a base portion 15 and a brace portion 16, with a hinge strip 17 formed on the brace portion 16, which like the hinge strip 10 is adhesively or otherwise secured to the rear face of the front portion 14. The base portion 15 also consists of converging sections 18 and 19 upwardly foldable in the same manner as the sections 7 and 8 and the portions 14, 15 and 16 as well as the sections 18 and 19 are provided by score or fold lines on the blank of Figure 5 which has additional transversely disposed score or fold lines 20 and 21 arranged on the front portion 14, so that the latter is adjustable to three inclined positions, two of which are shown in Figure 4.

The front portion 14 is shown as being free from article supporting or fastening means, so that the form of Figure 4 can be used for advertising purposes only, or in other words will act in the capacity of a sign, but the front portion 14 can be plain and cut out to provide fastening or supporting means to fit articles of any kind, that is the form of Figure 4 can be sold without any indicia on the front portion 14 and the purchaser can provide the cut out portions and apply any indicia desired.

The blank of the form of Figures 6, 7, 8 and 9 has score or fold lines 22, 23 and 24, as shown in Figure 9 to provide a front or body portion 25, a base portion 26 and a brace portion 27, the base portion 26 being identical to that of the form of Figures 1 and 2, but the front portion 25 is slit transversely as at 28 for the passage of a flap therethrough, that is formed on the brace

portion 27 between hinge strips or tongues 30, the strips 30 being adhesively or otherwise secured to the rear face of the front portion 25, as best shown in Figure 7, after the flap 29 is inserted through the slit 28. The flap 29 is arranged horizontally and has a row of openings 31 therein for receiving writing implements such as pencils or like shaped articles, the openings being made relatively small so that the edges thereof will set up a frictional engagement with the articles to hold the latter against removal or displacement with respect to the flap 29.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A display device comprising a relatively large front portion, a relatively narrow base portion including upwardly foldable hinge sections and hinged to the lower edge of the front portion for disposal rearwardly therefrom, a brace portion hinged to the rear edge of the base portion, hinge means formed on the brace portion and fixed to the rear face of the front portion for cooperation with the base and brace portions to support the device in displayed position with the front portion at a rearward inclination, a flap struck from the front portion and extending forwardly therefrom in a horizontal plane, said flap having openings therein arranged in row formation, means struck from the front portion below the flap to provide pockets aligned with the openings for cooperation therewith to receive and support articles to be displayed.

2. A display device comprising a front portion, a base portion including foldable sections and hinged to the lower edge of the front portion for disposal rearwardly therefrom, a brace portion hinged to the rear edge of the base portion and hinged to the rear face of the front portion for cooperation with the base portion for supporting the device in displayed position with the front portion at a rearward inclination, a relatively narrow flap struck and extending forwardly from the front portion for disposal in a horizontal plane, said flap having a row of openings therein, and substantially triangular shaped ears struck from the front portion and arranged in pairs to provide substantially V-shaped pockets for cooperation with the openings to receive and support articles to be displayed.

DALLAS V. LISLE.
